11 Claims. (Cl. 214—6)

1

The invention relates to improvements in or relating to card handling machines, particularly punched card machines in which cards after having passed through the machine are collected in receiving boxes. More particularly still, this invention relates to sorting machines for punched cards.

In sorting machines the time required for removing the cards from the receiving boxes after a sorting operation is lost time. Further sorting could take place for any receiving box immediately after the sorted cards have been removed therefrom. However, up to now this has not been possible because the cards from the other receiving boxes of the machine must be removed before a new cycle can be started.

This lost time will, in relation to the total sorting time, be of a relatively greater amount, as the speed of the machine increases and the number of the receiving boxes is larger e. g. in alphabetical sorting machines.

The present invention has for a particular object the elimination of the time required for emptying the receiving boxes as much as possible, so that sorting can take place substantially without loss of time.

According to this invention the pile of cards of a receiving box to be emptied is pushed aside by means of a transport element so far that the first occupied place is made free for immediately receiving new sorted cards.

For example, if 3200 cards are to be sorted in a machine adapted to deal with 32,000 cards an hour, 6 minutes are required for the actual sorting operation. If the time for taking out and laying down each pile of cards of a receiving box after sorting is, on the average, 2 seconds, then for a machine having 64 compartments a time of 128 seconds or more than 2 minutes is required for removing the sorted cards.

From the above it will be evident that more than 25% of the machine time is lost. On the other hand, if the time for pushing out the sorted cards according to the present invention is only 2 seconds for all compartments then less than 1% of the sorting time is lost.

A device according to this invention is illustrated in the drawings, wherein:

Fig. I is an elevational view of a device according to this invention with an empty receiving box;

Fig. II is a view like Fig. I, the receiving box however being filled;

Fig. III is an elevational view of the device looking in from the left of Fig. I with the ex-

2

treme left hand box empty and those to the right thereof at least partly filled;

Fig. IV is another embodiment of the invention in elevation.

- 5 In Fig. I a supporting element comprising a carriage 2 is guided along a bar 1 by means of rollers 3 and 4, the said element acting as a receiving element for the cards, or having the receiving element thereto attached.
- 10 Between the horizontally extending guides 5 and 6 of the receiving element is a slideable part 7 which, at its end adjacent carriage 2 has an upstanding part 8. To the underside of part 7 a toothed rack 9 is fixed.
- 15 The parts 5 and 6 and the slideable part 7 constitute the bottom of the card receiving box, which adjusts itself along bar 1 according to the height of the pile of cards resting thereon. The helical spring 10 which bears the weight of the bottom and of the pile of cards resting thereon, may, if desired, be arranged within the guiding bar 1, which then of course is hollow, or may be positioned externally of the bar.
- 20 Extending transversely with respect to the guides 5 and 6 and above the guides there is a bar 11, which is fixed to the upper ends of links 11 and 12. The links are pivotally connected at their lower ends to two arms 13 pivoting on a shaft 14. These arms each bear a roller 15.
- 25 The rollers 15 cooperate, by means of springs, between their ends (not illustrated) with cam disks 16, having nose portions 16a, which are fixed to a shaft 17. This shaft 17 may be rotated by hand, for example by means of a crank handle, in the direction of the arrow and afterwards be moved back again. On the shaft 17 a toothed wheel 18 is mounted for free rotation, which is provided with a groove or slot 19 through which a pin 20 passes that is fixed to the disk 16. The
- 30 toothed wheel 18 comprises an untoothed part 21 and is rotatable under the influence of a flexible drawing cable 23, passing over a roller 24 and carrying a weight 22. The toothed wheel 18 meshes with a pinion 25, which is fixed to the shaft 26.
- 35 Most of the described parts designated by reference numerals from 11 to 25 are made in duplicate, that is to say one is provided at each side of the machine (see Fig. III): and on the shaft 26 a plurality of toothed wheels 27 are arranged, one for each card receiving box.
- 40 The toothed wheels 18, which are operated by the drawing force of the weight 22, are arranged in such a way that the untoothed part 21 limits the rotation of the toothed wheel 18 so that it

- 45 50 55

has an off-position as indicated in Fig. I. The cam disks 16 are in the off-position illustrated in Fig. I, the pin 20 being nearly at the one end of the slot 19.

At the left, before each outlet of the receiving boxes when the boxes are in their lowered position, a receiving part 28 is arranged having a downwardly bent end 29 (Figures I-II).

The operation of the device as described is as follows:

When sorting, the cards are falling according to the punched holes into the corresponding receiving boxes and are laid down on the bottom thereof. As the height of the pile of cards in a box increases, the box will move downwardly against its supporting spring *a*. If at the end of the sorting operation, the cards must be taken out of the receiving boxes, the shaft 17 is rotated by means of a handle in the direction of the arrow. When shaft 17 is so rotated, the disks 16 are moved, the pins 20 being moved through the grooves or slots 19 of the toothed wheels 18. The disks 16 press the rollers 15 downwardly and thereby also the bar 10. Thereby all the carriages 2 and their connected boxes are pushed downward, regardless of the number of cards in each, to such an extent that the teeth of the racks 9 will engage the toothed wheels 27. This position is reached when the disk 16 has been rotated about 90° from its Fig. I position.

Further rotation of shaft 17 and disk 16 picks up wheel 18 by the pin 20 so that the shaft 26 is also rotated. Rotation of shaft 26 will cause all the toothed wheels 27 arranged thereon to rotate also, and because these toothed wheels 27 mesh with the racks 9, the latter are moved to the left.

Movement of racks 9 to the left also moves the slideable parts 7 connected thereto and by this displacement, the cards in the corresponding boxes are moved by the upstanding part 8 and guided by the obliquely rising end 29 to a somewhat higher position on the receiving part 28. The rotation of shaft 17 can continue until the nose 16a of the disk 16 is arrested by the roller 15. The cards are then lying fully on the receiving part 28. If now the handle and thus the shaft 17 is rotated back, toothed wheel 18 and its connected parts will remain under the influence of the weight 22 and thus turn back with the disk 16. Due to this rotation the toothed wheels 27 are also turned back and the slide parts 7 thereby are moved again to their right-hand position. The cards, however, have been raised to some extent so they no longer rest on the slide part 7 and therefore are not moved back therewith.

When the backward movement of the toothed wheels 18 and 25 cannot be continued because the teeth of the toothed wheel 25 meet the un-toothed part 21 of the wheel 18 the said wheels stop. The disk 16 can move further backwardly, the pin 20 moving in the slot 19. Due to this further movement of disk 16 the rollers 15, following the circumference of the disks 16, again move upward and with them also the arms 13, links 11 and 12 and bar 10 all move upwardly under the influence of the spring (not shown).

This upward movement of bar 10 enables the carriages 2 to be moved upwardly by springs or until they have reached their uppermost position.

At the end of the described operation of the device according to the invention, all cards are, at one and the same time, delivered to the re-

ceiving parts 28, and all receiving boxes are empty. In order to be able to commence sorting on the following column, it is only necessary to put the cards of the first receiving box in the supply box, after which sorting may start immediately. Successively the further cards are placed in the supply box in the normal order of succession during sorting. The time between two successive sorting processes is thus only the brief time required for simultaneously pushing out the cards from the receiving boxes and inserting the first pile of cards into the supply box.

In the foregoing description, it was supposed that sorting is completed before one of the receiving boxes is filled so far that the machine stops automatically. If there are many cards of one or more kinds and as a result one or more receiving boxes are filled before sorting is completed it may be suitable to stop the machine and to remove all cards from the receiving boxes before sorting is continued. After sorting, all cards of the similar receiving boxes may be put together. Under certain circumstances it may occur that certain receiving boxes always become filled whereas only a few cards arrive at the other ones. In such a case it would cause unnecessary work repeatedly to stop the machine and remove the cards.

The device according to the invention may be altered in such a way that in case of an operation of the nature just described only those receiving boxes are emptied, which are filled completely or nearly completely. A device altered in such a manner has been illustrated in Figure IV.

Between the guides 5 and 6 a sliding part 7 provided with an upturned portion 8 is arranged, adapted to push the cards to the left as described for the first modification. At its underside the sliding part 7 carries a projection 30, this projection being provided with notches. These notches are adapted for engagement by a catch 31 under the influence of a spring 32. This catch 31 is fixed to a slide 33, comprising an opening 34 through which the projection 30 may pass. The slide 33 is pivotably connected to a rod 35 which is pivotally mounted between two arms 37 pivoting on a shaft 36. By means of springs 38, the said arms, and on which rollers 39 are mounted, are pulled as far as possible to the right with regard to Figure IV so that the rollers 39 rest against the cam disks 40. In the position of rest these various parts take the position illustrated in Figure IV, so that the slide 33 takes its outermost position. With the slide in this position the catch 31 with its lower part rests against a fixed stop 41, causing the catch 31 to be pushed against the force of the spring 32 out of the path of the projection 30 on the sliding part 7. The cam disk 40 is so shaped that the active portions sloping upwards and downwards respectively each take 90°, whereas the remaining part of the circumference is of constant diameter. The cam disk 40 is driven as follows:

By a driving gear wheel 42 a gear wheel 43 is rotated, the latter being connected to a disk 44 comprising a recess 45. The gear wheel 43 and the disk 47 rotate freely on a shaft 51. The disk 47 carries a pawl 46 adapted to cooperate with and to engage the recess 45 when the pawl 46 is released by a lever 49. A spring 48 continuously urges the pawl 46 into this recess engaging position, in which the disks 44 and 47 are coupled together by said pawl. It will be

evident that, when the recess 45 is thus engaged by the pawl 46, the disk 47 will rotate when the disk 44 rotates. Since the disks 40 and 47 are fixed to the shaft 51, the shaft 51 and disk 40 will likewise rotate with disk 47. The member 49 is pivotably mounted on a shaft 62 and capable of being operated by a key 50. Two brackets 37 carrying rollers 39 are necessary, the rollers 39 being driven by two cam disks 40. The member 49 is operable to keep the pawl 46 out of the path of the disk 44. On the same shaft 51 also the gear wheel 52 and the coupling disk connected thereto is mounted for rotation.

When in operation, the key 50 is pressed downwardly, the pawl 46 is freed and under the influence of spring 48 engages the recess 45 on disk 44, and thus, the shaft 51 and the cam disks 45 are driven by the continuously rotating gear wheel 42, with the result that both cam disks 40 will perform one revolution. Consequently both arms 37 are moved first to the left and thereafter again to the right by means of the rollers 39 against the action of the springs 38. All slides 33 connected to the rod 35 follow the same movement. At the end thereof they are again in the position of rest as illustrated. The device described operates as follows:

When one or more card receiving boxes are filled, the said filled boxes move into their lowest position. As a result, a contact is closed in a known manner stopping the sorting operation. In this lowest position of the boxes the projection 30 has passed the opening 34. When the boxes are not entirely filled the projections are only partway through the openings, and when less than a predetermined number of cards are in a box, its projection is not in the opening at all.

If, now, the key 50 is pressed, then the one-revolution coupling comes into action, and, in the manner described, all sliding parts 7, of which the projection 30 has entered the receiving opening 34, are moved to the left and thereafter to the right. Immediately upon the movement to the left, the catches 31 are freed, and enter into one of the notches of the adjacent projection 30. The sliding parts 7 are then prevented from moving upward, even after the cards are pushed on to the receiver 28. The sloping edges 29 of course must be made in such a way that in each position of the sliding part 7 the cards may be pushed thereon.

At the end of the backward movement of the parts slides 33, the catches 31 are again pushed out of the notches of the projections 30, so that the boxes may again return into their upper positions. The cards which are pushed out now may be laid aside during the rest of the sorting process in order to be added later on to the corresponding cards.

With the device shown in Figure IV it is also possible to empty all receiving boxes independent of the number of cards contained therein. This will be necessary for example, at the end of a sorting operation on a special column. In this instance, a subsequently described device is used which, if desired, comes into action automatically when the supply box is empty. The gear wheel 42 referred to above meshes with a further gear wheel 52 mounted for rotation on a shaft 53. The gear wheel 52 carries a disk 54, provided with a recess 55. The shaft 53 carries a disk 56 provided with a catch 57, adapted to enter the recess 55 of the disk 54. The catch 57 is under the influence of a tension spring 58 and may be freed by means of an intermediary member 59 and a knob 60 fixed thereto.

On the shaft 53 two cam disks 61 are mounted, at each end of the shaft. These disks cooperate with rollers 15 of the arms 13. These arms 13 are pivoted at one end on a shaft 14, and at their other ends are connected by means of links 11 and 12 to a rod 10 arranged above the carriage 2, carrying the guiding members 5 and 6 for the sliding part.

By means of springs a, these carriages 2 are held in their upper position and this also holds the rollers 15 of the levers 13 against the circumferences of the disks 61. On the circumference of the cam disk 56 a roller 62 bears which is rotatably mounted on the arm 49 which, in the lower position keeps the catch 46 out of the path of the disk 44. The described arrangement constitutes a one-revolution coupling.

The position of the disks is such that first the pawl 59 is made free upon pressing of the key 60 and after rotation of the disks through 90° catch 46 is released. The couplings thus come into action one after the other. When the locking pawl 59 is moved out of the reach of the coupling catch 57, by pressing key 60 the catch will fall into the recess 55, due to which the cam disks 61 will be rotated by the gear wheel 52. The rollers 15 and with them the arms 11 and 12 are thereby lowered, and by means of the rod 10 push down all carriages 2 and thus also the guides 5 and 6 and the sliding parts 7. After the disks 61 have rotated through 90°, the rollers 15 have reached the highest part thereof, and remain in this position for a further 180° of rotation of the disks. The cam 56 having reached the roller 62 after about 90° of rotation of the disk 61, pushes the roller to the left, and consequently the arm 49 releases the catch 46. The disk 40 now starts to rotate and, consequently, the levers 37 are moved to the left. After a rotation of the disk 40 through 90°, all slides 33 have come in the position wherein the cards are pushed out of the receiving boxes on to the receivers 23. Thereupon the levers 37 again move to the right due to the sloping edge of the disk 40 and the tensile force of the spring 38, till the slides have come back in to the position of rest as shown. Thereupon the rollers 15 can rise again by a further rotation of the disk 61 and with them also the boxes which are to bear the cards.

It will be understood that in the last described action the projections 30 and the catches 31 are not necessary, because the parts 5—6—7 which are bearing the cards are held in the lower position during the required time by the rod 10.

In the embodiment according to Fig. IV a device has been provided for preventing the key 60 from being pressed as long as sorting has not been finished, that is to say while cards are still in the supply box. A feeler 64 extends through the side wall 63 of the supply box pressing against the pile of cards under the influence of a spring 65. The other end of this feeler is beneath the end of the locking pawl 59, so that it cannot move downward. When the card supply box is empty the feeler 64 is moved to the right releasing the pawl 59. When the latter is kept in the upper position by means of a spring 66, the device may be started by pressing the key 60. If the spring 66 is reversed so it will pull the pawl 59 into the lower position, the device will start automatically when the feeler moves to the right. The advantage of the last described arrangement consists in that during sorting, the key 60 never can be pressed down, while by pressing the key 50 certain of the compartments can be emptied.

What I claim is:

1. An apparatus for sorting cards, comprising in combination, a plurality of receptacles comprising vertically reciprocable carriages, horizontal guide means projecting from said carriages, bottoms on said guide means for receiving the sorted cards, the bottom of each receptacle being slideable on the guide means therefor, resilient means supporting each carriage yieldable under the weight of cards delivered to the associated bottom, receiving means near a lower position of each receptacle for receiving sorted cards from the bottom thereof, discharge means for reciprocating each said bottom, when the associated receptacle is in the said lower position, and actuating means operable to actuate said means at the said lower position of the respective receptacle for transferring the sorted cards from said respective bottoms to said receiving means.

2. An apparatus for sorting cards, comprising in combination, a plurality of receptacles for respectively receiving the sorted cards, each receptacle being adapted to support a pile of sorted cards and being movable from an upper position of the respective receptacle to a lower position, receiving means spaced from said lower position of said receptacles for receiving sorted cards from the bottom of said receptacles, an actuating member common to all the receptacles and operable at one and the same time to move all of the receptacles to said lower position and to hold them therein and discharge means operable in cooperation with said control means to effect the discharge of cards from said bottoms to said receiving means, said discharge means being operable only when said receptacles are in their said lower position.

3. An apparatus for sorting cards, comprising in combination, a plurality of receptacles for respectively receiving the sorted cards, the bottom of each receptacle being adapted to support a pile of sorted cards and being reciprocable in a vertical and a horizontal direction, receiving means spaced from the normal loading position of said receptacles for receiving sorted cards from the bottom of said receptacles, control means operable to control the movement of the bottoms of all the receptacles from said loading positions first in a vertical and then in horizontal direction into discharging position adjacent said receiving means, said control means including transporting means for each receptacle operable to move the respective receptacle bottom, from said loading positions into discharge positions in card transferring relation with said receiving means, said transporting means including first toothed means respectively associated with the bottom of the respective receptacle, and second toothed means arranged for cooperation with said first toothed means thereby to cause said transporting means to effect said horizontal movement of the respective receptacle bottoms in response to the actuation of said control means.

4. An apparatus for sorting cards, comprising in combination, a plurality of receptacles for respectively receiving the sorted cards in piles, the bottom of each receptacle being adapted to support a pile of sorted cards and each receptacle being movable in a substantially vertical direction from its upper or empty position into a downward or filled position and vice versa, resilient means supporting said receptacles yieldably under the weight of the cards therein, each receptacle including a part movable in a substan-

tially horizontal direction in the lower or filled position of each receptacle for transporting sorted cards from the bottom of the respective receptacle, actuating means including a reciprocable member for actuating said part of each receptacle when the respective receptacle is in its lower or filled position, and means connected to said part of each receptacle and operable to pass through an opening in said reciprocable member for establishing driving connection with said actuating means.

5. An apparatus for sorting cards, comprising in combination, a plurality of receptacles for respectively receiving the sorted cards, the bottom of each receptacle being adapted to support a pile of sorted cards and being movable in a substantially vertical direction from its upper or empty position into a lower or filled position and vice versa, resilient means supporting the bottom of each of said receptacles yieldable under the weight of cards on the bottom to permit movement of the bottom from said upper position toward said lower position, receiving means near said lower position of each bottom displaced horizontally therefrom for receiving sorted cards from the bottom of the respective receptacle, discharging means respectively associated with the bottom of each of said receptacles and movable together with the bottom pertaining thereto from said lower position horizontally into a discharge position and vice versa, said cards on the bottom being transferred to said receiving means in response to movement of the bottom into discharge position, actuating means including a reciprocable member for actuating said discharging means when the respective bottom is in its discharging position, means connected to said discharging means and operable to pass through an opening in said reciprocable member for establishing driving connection with said actuating means, and a locking mechanism provided between said last mentioned means and said reciprocable member to maintain driving connection between said discharging means and said actuating means during the discharge of cards from the respective bottom to said receiving means.

6. An apparatus for sorting cards, comprising in combination, a plurality of receptacles for respectively receiving the sorted cards, the bottom of each receptacle being adapted to support a pile of sorted cards and being movable in a substantially vertical direction from its upper or empty position into a lower or filled position and vice versa, resilient means governing the movement of the bottom of each of said receptacles from said upper position into said lower position, and being yieldable under the weight of cards on the respective bottom, receiving means near said lower position for receiving sorted cards from the bottom of the respective receptacle, discharging means respectively associated with the bottom of each of said receptacles and movable together with the bottom pertaining thereto from said lower position into card transferring position with said receiving means and vice versa, actuating means including a reciprocable member for actuating said discharging means when the respective bottom is in its lower position, means connected to said discharging means and operable to pass through an opening in said reciprocable member for establishing driving connection with said actuating means, and a locking mechanism provided between said last mentioned means and said re-

ciprocable member to maintain driving connection between said discharging means and said actuating means during the discharge of cards from the respective bottom to said receiving means, said reciprocable member comprising a catch for cooperation with notches in said last mentioned means.

7. An apparatus for sorting cards, comprising in combination, a plurality of receptacles for respectively receiving the sorted cards, the bottom of each receptacle being adapted to support a pile of sorted cards, each bottom being resiliently supported in an upper or empty position of the respective receptacle and movable under the weight of cards therein to a lower or filled position, receiving means spaced from said lower position of said bottoms for receiving sorted cards therefrom, an actuating member common to all bottoms and operable to move, at one and the same time, all of the said bottoms to the said lower position thereof, discharge means associated with the bottoms of said receptacles movable for discharging sorted cards from said bottoms to said receiving means, and control means operable successively to bring about movement of said bottoms to their respective lower position by said actuating member, then to cause actuation of said discharge means to discharge the cards from said bottoms to the receiving means, and then to allow return of said emptied bottoms to their upper positions.

8. An apparatus for sorting cards, comprising in combination, a plurality of receptacles for respectively receiving the sorted cards, the bottom of each receptacle being adapted to support a pile of sorted cards, each bottom being resiliently supported in an upper or empty position of the respective receptacle and movable under the weight of cards therein to a lower or filled position, receiving means spaced from said lower position of said bottom for receiving sorted cards therefrom, an actuating member common to all bottoms and operable to move, at one and the same time, all of the said bottoms to said lower position thereof, discharge means associated with the bottoms of said receptacles for discharging sorted cards from said bottoms to said receiving means, first driving means for operation of said actuating member, second driving means for operation of said discharge means, and operating means adapted to be brought into driving engagement with said first and second driving means and operable on each of said driving means during a complete cycle of operation.

9. An apparatus for sorting cards, comprising in combination, a plurality of receptacles for respectively receiving the sorted cards, the bottom of each receptacle being adapted to support a pile of sorted cards, each bottom being resiliently supported in an upper or empty position and being yieldable under the weight of cards therein to a lower or filled position, receiving means spaced from said lower or filled position of said bottoms for receiving sorted cards therefrom, an actuating member common to all bottoms and

operable at one and the same time to move all of the bottoms into the said lower position thereof, discharge means associated with the bottoms of said receptacles for discharging sorted cards from said bottoms to said receiving means, a first one revolution driving mechanism for driving said actuating member, a second one revolution driving mechanism for driving said discharging means, and means associated with said second driving mechanism for initiating operation thereof in response to the actuation of said first driving mechanism.

10. An apparatus for sorting cards, comprising in combination, a plurality of receptacles for respectively receiving the sorted cards, the bottom of each receptacle being adapted to support a pile of sorted cards and being movable from an upper or empty position of the respective receptacle to a lower or filled position, receiving means spaced from said lower position of said bottom for receiving sorted cards therefrom, an actuating member common to all bottoms and operable at one and the same time to move all of the bottoms to said lower position thereof, discharge means associated with the bottoms of said receptacles for discharging sorted cards from said bottoms to said receiving means, a first one revolution driving mechanism for driving said actuating member, a second one revolution driving mechanism for driving said discharging means, means associated with said second driving mechanism for initiating operation thereof in response to the actuation of said first driving mechanism, and means operable for making said last mentioned means ineffective.

11. An apparatus for sorting cards, comprising in combination, a supply box, a plurality of receptacles for respectively receiving sorted cards from said supply box, the bottom of each receptacle being adapted to support a pile of sorted cards and being movable from an upper or empty position of the respective receptacle to a lower or filled position, receiving means spaced from said lower position of said bottom for receiving sorted cards therefrom, an actuating member common to all bottoms and operable at one and the same time to move all of the bottoms to said lower position thereof, a feeler element to detect the presence of cards in said supply box, and means operated by said feeler element for preventing operation of said actuating member in response to the presence of cards to be sorted in said supply box.
